(57) **CLAIM**

The ornamental design for a cat litter box as shown and described.

DESCRIPTION

FIG. 1 is a perspective view of a cat litter box;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view of the cat litter box in an exploded state; and,
FIG. 9 is another perspective view of the cat litter box in an exploded state.
The broken lines in the drawings depict portions of the cat litter box that form no part of the claimed design.
